UNITED STATES PATENT OFFICE.

ROY J. WENSLEY, OF EDGEWOOD, PENNSYLVANIA, ASSIGNOR TO WESTINGHOUSE ELECTRIC & MANUFACTURING COMPANY, A CORPORATION OF PENNSYLVANIA.

AUTOMATIC SUBSTATION.

Application filed September 23, 1924. Serial No. 739,262.

My invention relates to automatic stations and particularly to stations comprising means for translating energy between two electric power circuits.

One object of my invention is to provide an electrical system comprising fully automatic means for causing a translating device to translate energy in either direction between two power circuits in accordance with predetermined conditions.

Another object of my invention is to provide a system, of the above-indicated character, in which a control and indicating station is connected to the translating station by only one wire in addition to the conductors of one of the power circuits.

Another object of my invention is to provide means, in a system of the above-indicated character, for regulating the field-magnet excitation of a translating device to control one or another characteristic of the device depending upon whether it is supplying energy to or receiving energy from its power circuit.

In certain electrical systems comprising both alternating-current and direct-current circuits, the alternating-current supply is the primary source of energy and the direct-current energy is largely obtained from translating devices that are operated from the alternating-current system. A part of the direct-current energy, however, is usually supplied from an independent source, such as one or more steam-driven generators or the like. Thus, it is almost always possible to obtain some direct-current energy even though the alternating-current source may fail.

In large industrial and manufacturing plants, such, for example, as steel mills, certain essential apparatus is driven by alternating-current motors and it is of prime importance that alternating-current energy shall always be available for operating these motors, as the discontinuity of this service may often involve great losses and sometimes danger to operators. Therefore, I propose means embodied in my present invention, whereby an alternating-current system may receive energy through translating devices from a direct-current system in emergencies, although the translating devices normally operate to receive energy from the alternating-current system and to supply energy to the direct-current system.

In practicing my invention, I provide two

power circuits, a translating device, and automatic means for connecting the translating device between the two circuits in response to predetermined conditions. One of the power circuits is an alternating-current circuit and the other a direct-current circuit and the translating device comprises an alternating-current dynamo-electric machine and a direct-current dynamo-electric machine. Under normal conditions of operation, the translating device is started and operated from the alternating-current circuit in response to a demand for load on the direct-current circuit. The direct-current machine is then driven by the alternating-current machine to supply energy to the direct-current circuit so long as such energy is required. When the operation of the translating device is no longer required, to supply energy to the direct-current circuit, its operation is automatically stopped after a predetermined interval of time.

I also provide means that become operative in the event that the voltage of the alternating-current circuit fails, whether or not the translating device is operating, to cause the direct-current machine to act as a motor to drive the alternating-current machine which acts as a generator to supply energy to the alternating-current circuit and to maintain the voltage thereof at its normal value. In the event that the voltage of the alternating-current circuit fails, when the translating device is not operating, the direct-current machine is automatically started and operated from the direct-current circuit and the alternating-current machine is connected to the alternating-current circuit to supply energy thereto.

I further provide means for manually controlling the operation of the translating device from any desired point, which point is connected to the local controlling apparatus of the translating device by means of only the two conductors of the direct-current circuit and a single additional control conductor. Switches are provided at the control point which will start, stop and lock out the translating device, as desired. An indicating device at the control point is also connected between only the conductors of the direct-current circuit and the single control conductor. This device indicates whether or not the translating device is operatively connected to the system and, where more

than one translating device is used, it may indicate just how many of the translating devices are operatively connected to the system.

5 My invention will be more clearly understood by reference to the accompanying drawings, in which

Figures 1, 2, 3 and 4, when placed end to end, from left to right as enumerated, form 10 a diagrammatic representation of an electrical system in which my invention is embodied, and

Fig. 5 comprises a definition of the symbols used and a list of certain of the apparatus shown in the previous figures of the drawings.

Referring to Figs. 1, 2, 3 and 4 of the drawings, an alternating-current circuit 1 and a direct-current circuit comprising conductors 2 and 3, are provided with an alternating-current dynamo-electric machine 4 and a direct-current-dynamo-electric machine 5, respectively. The rotating members of these machines are mechanically connected 25 to each other by means of a shaft 6 that permits either machine to drive the other. The alternating-current machine 4 may be connected to the alternating-current circuit 1 through a starting circuit interrupter 7 and an auto-transformer 8 or directly through a 30 running circuit interrupter 9. One terminal of the direct-current machine 5 is connected to the conductor 3 of the direct-current circuit through an interpole field-magnet winding 10 and a series field-magnet winding 11, and the other terminal of the direct-current machine 5 is connected to the conductor 2 of the direct-current circuit through resistors 12, 13 and 14, series load relays 15, 16 and 40 17, circuit interrupters 18, 19, 20 and 21 and a shunt 22.

Under normal conditions, when the voltages of both the alternating-current circuit and the direct-current circuit are near their 45 normal values, the alternating-current machine 4 is automatically started and operated as a synchronous motor to drive the direct-current machine 5 as a generator to supply energy to the direct-current circuit. This 50 operation is automatically initiated in response to a demand for energy on the direct-current circuit and is automatically stopped when this demand for energy remains below a predetermined value for a predetermined 55 interval of time. In the event, however, that the voltage of the alternating-current circuit 1 falls below a predetermined value, the direct-current machine 5 is operated as a motor from the direct-current circuit to drive the 60 alternating-current machine 4 as a generator to supply energy to the alternating-current circuit 1 until the normal source of alternating-current energy again becomes available to maintain the voltage of the circuit 1 at substantially its normal value.

If the voltage failure of the circuit 1 occurs while the alternating-current machine 4 is operating as a motor to drive the direct-current machine 5 as a generator, the direction of energy traversal of the machines 4 and 5 will simply reverse to cause the machine 5 to operate as a motor and the machine 4 as a generator. If the voltage failure occurs while the machines 4 and 5 are at a standstill, however, automatic controlling equipment immediately becomes operative to start the direct-current machine 5 as a motor from the direct-current circuit. The speed of the machines 5 and 6 is automatically regulated to a predetermined value and the circuit interrupter 9 is then closed to permit the machine 4 to supply energy to the circuit 1 until the normal source of alternating-current energy again becomes available.

In order that remote manual control may be superimposed upon the automatic control of the translating apparatus, I provide a control and indicating equipment 23 comprising push-button switches 24 and 25, a single-pole double-throw knife switch 26 and 90 an indicating device 27. The only electrical connections between the control and indicating equipment 23 and the apparatus in the translating station are made through the conductors 2 and 3 of the direct-current circuit 95 and a single additional control conductor 28. When availability of both automatic and manual control of the translating apparatus is desired, the knife switch 26 is closed in its lower position, as indicated in the drawing. 100 If it is then desired to start the operation of the translating apparatus when there is not a sufficient demand for energy on the direct-current circuit to effect automatic starting of the apparatus, the push-button 25 is depressed. In like manner, if it is desired to stop the operation of the apparatus immediately at any time while it is operating, the push-button 24 is depressed. If it is desired to entirely preclude operation of the apparatus either in response to the functioning of the automatic equipment or in response to manual operation of the push-button 25, the knife switch 26 is closed in its upper position. The indicating device 27 is adapted to indicate 110 when the translating device is operatively connected between the power circuits and, in the event that more than one translating apparatus is provided, this device indicates how many of the apparatus are operatively connected between the power circuits. 115

It will be understood that the conductors 2 and 3 of the direct-current circuit are usually the conductors of a network which traverses all of an industrial or manufacturing plant and that therefore they are available for connection at any desired point within the plant. Consequently, the only separate conductor which must be installed to connect the remote control and indicating equipment 120

with the local controlling equipment of the translating devices is the control conductor 28.

In describing the operation of the electrical system embodying my invention, let it first be assumed that the dynamo-electric machines 4 and 5 are at a standstill and are disconnected from their respective circuits. Upon a demand for energy upon the direct-current system in excess of the capacity of the translating devices that are already supplying energy thereto, the voltage between the conductors 2 and 3 falls to such a value that an underload relay 29, (illustrated in circuit A, Fig. 3) permits its switch 29-1 (circuit B-2) to open and its switch 29-2 (circuit B) to close. The operating coil of a time-delay relay 30 (circuit B) is thereupon connected between the conductors 2 and 3 of the direct-current circuit to energize the same. This circuit is completed because switch 31-1 of an over-speed device 31, switch 32-1 of a lockout relay 32, switch 33-1 of an alternating-current thermal relay 33, switch 29-2 of the undervoltage relay 29 and switch 34-1 of an auxiliary master relay 34, are closed. The time-delay relay 30 therefore begins to actuate its switch 30-1 (circuit B-5) toward its closed position.

If the low-voltage condition of the direct-current circuit continues for the interval of time in which the relay 30 is adjusted to close its switch 30-1, the operating coil of a master relay 35 (circuit B-5) is energized. The energizing circuit for the coil of relay 35 extends from conductor 2 through switches 31-1 and 32-1, (circuit B), switch 32-2 (circuit B-5) of the lockout relay 32, switch 36-1 of a stopping relay 36, a resistor 37, operating coil of relay 35, switch 30-1 and an auxiliary switch 9-1 of the running circuit interrupter 9 to conductor 3.

The relay 35 thereupon closes its switches 35-1, (circuit B-3), 35-2 (circuit B-54) and 35-3 (circuit D), and opens its switch 35-4 (circuit V-21). The switch 35-2 so shunts the switches 31-1 and 9-1 as to maintain energization of the relay 35 after either or both of the switches 30-1 and 9-1 are opened. The closing of the switch 35-3 connects the operating coil of the auxiliary master relay 34 (circuit D) between the conductors 2 and 3 of the direct-current circuit through a resistor 38. The operating coil of a control relay 39 (circuit D-1), to be described later, is connected directly between the conductors 2 and 3 when the switch 35-3 is closed. The auxiliary master relay 34, when energized, opens its switches 34-1 (circuit B) and 34-2 (circuit B-52) and closes switches 34-3 (circuit C) and switch 34-4 (circuit AA).

The closing of switch 34-3 (circuit C) connects an auxiliary conductor 2A, to which a number of control apparatus to be de-

scribed later, are connected to the conductor 2 of the direct-current circuit. When the conductor 2A is energized from the conductor 2, another auxiliary control relay 40 (circuit E) is energized. The circuit of the relay 40 extends through switch 41-1 of a relay 41 (circuit V) to be described later. When the operating coil of the relay 40 is energized, switch 40-1 (circuit F) is closed to effect energization of the operating coil of a starting circuit interrupter control relay 42. The energizing circuit of the relay 42 extends from conductor 2A through switch 43-1 of a transfer relay 43 (circuit K), an auxiliary switch 7-1 of the starting circuit interrupter 7, switch 44-1 of a time-delay cut-off relay 44 (circuit G-1), and switch 40-1 of the relay 40 to conductor 3 of the direct-current circuit.

When the operating coil of the relay 42 is thus energized, two switches 42-1 (circuit F) and 42-2 (circuit G) are closed thereby. The switch 42-1 so shunts the switch 7-1 of the starting circuit interrupter 7 as to maintain energization of the coil of relay 42 after the circuit interrupter 7 is actuated to its closed position. The switch 42-2, when closed, connects the closing coil 7A of the starting circuit interrupter 7 between the conductors 2 and 3 of the direct-current circuit to effect closing of the interrupter 7. At the same time, that the closing coil 7A is energized, the operating coil of the time-delay cut-off relay 44 is also connected between the conductors 2 and 3. This circuit extends through switch 42-2 (circuit G) and an auxiliary switch 56-1 of a running circuit interrupter control relay 56 (circuit L) to be described later. After a predetermined interval of time, the time-delay relay 44 opens its switches 44-1 (circuit F), and 44-2 (circuit L) and closes switch 44-3 (circuit J). The operation of the switches 44-2 and 44-3 is ineffective at this time in the sequence and their function will be described later.

When the switch 44-1 is opened, the circuit of the operating coil of the relay 42 (circuit F) is opened to permit this relay to return to its de-energized position, in which its switches 42-1 and 42-2 are open. The opening of the switch 42-1 (circuit F) interrupts the holding circuit for the operating coil of the relay 42 and the opening of the switch 42-2 interrupts the energizing circuits for the closing coil 7A of the starting interrupter 7 and for the operating coil of the cut-off relay 44 (circuits G and G-1).

The starting circuit interrupter 7 is now closed and remains latched in its closed position until it is tripped open. When the circuit interrupter 7 is closed, alternating current energy is supplied to the armature windings 4A of the dynamo-electric machine 4 from the circuit 1 through the auto-transformer 8. The auto-transformer 8 serves to

reduce the potential which is applied to the machine 4 during the starting period thereof. During this period, a field-magnet winding 4-B of the machine 4 is disconnected from its energizing circuit by a switch 45-1 of a field-magnet winding contactor 45, the operating coil of which is shown in circuit J. The operating coil of the contactor 45 is de-energized until later in the sequence. A 10 second switch 45-2 of the contactor 45, that is closed when the operating coil of the contactor is de-energized, closes a shunting circuit for the field-magnet winding 4-B, comprising a resistor 46 and the operating coil 15 of an inductive relay 47.

Since the field-magnet winding of the machine 4 is shunted by a resistor and is not energized from an external source when the starting circuit interrupter 7 is closed, the 20 machine 4 starts to operate as an induction motor and drives the direct-current machine 5 by means of the shaft 6. At this time, however, there is no load on the direct-current machine and, consequently, the alternating-current machine 4 increases in speed until it 25 approaches synchronous speed. Until approximately synchronous speed is reached, the current that is induced in the field-magnet winding 4-B from the armature windings 4-A traverses the operating coil of the relay 47 and holds the switch 47-1 (circuit J) of this relay open to preclude energization of the operating coil of the contactor 45. When the speed of the machine approaches 30 synchronism, however, the current that is induced in its field-magnet winding falls to a value that is insufficient to maintain the switch 47-1 of the relay 47 open. This switch therefore closes to connect one terminal of the operating coil of the contactor 45 to the control conductor 2A.

When energy is supplied to the armature windings 4A of the alternating-current machine 4, due to the closing of the starting circuit interrupter 7, an alternating-current reverse energy relay 48 (Fig. 1) opens its switch 48-1 (circuit U) and closes its switch 48-2 (circuit U). The switch 48-1 when closed, close-circuits the operating coil of an auxiliary relay 49 (circuit U) to preclude energization thereof. When the switch 48-1 is open, however, this close-circuit is removed to permit energization of the operating coil of the relay 49. The switch 48-2 is connected in series with the operating coil of the relay 49 to establish an energizing circuit therefor when this switch is closed.

One terminal of the operating coil of relay 49 is connected through a resistor 50 and a conductor 51 to one terminal of the direct-current dynamo-electric machine 5. As the speed of the machine 5 increases, due to the operating of the alternating-current machine 4, the voltage between its terminals builds up to a value sufficient to operate va-

rious controlling apparatus in the station. Thus, when the switch 48-1 is opened and the switch 48-2 is closed, the operating coil of the relay 49 is energized from the direct-current machine 5. The energizing circuit 70 for this relay extends from conductor 51 through resistor 50, coil of relay 49, switch 48-2 and switch 39-1 (circuit S) to the conductor 3 of the direct-current circuit to which the other terminal of the direct-current machine 5 is connected, as previously described. As has been previously described, the switch 39-1 of the relay 39 was closed when the operating coil of this relay was energized simultaneously with the energization of the auxiliary master control relay 34 (circuits D and D-1).

When the operating coil of the relay 49 is energized, as described above, this relay opens a switch 49-1 (circuit V) and closes switches 85 49-2 (circuit U) and 49-3 (circuit J-1).

The function of the switch 49-1 will be described later. The switch 49-2 is connected in parallel relation to the switch 48-2 to maintain a holding circuit for the operating 90 coil of the relay 49. The closing of the switch 49-3 completes the energizing circuit of the operating coil of the contactor 45, (circuit J) to effect opening of the switch 45-2 and closing of the switches 45-1 and 45-3, which 95 have been previously described. Another switch 45-4 (Fig. 1) which will be described later, is also closed when the operating coil of the contactor 45 is energized. When the switch 45-2 is opened, the circuit shunting 100 the field-magnet winding 4B of the alternating-current machine 4 is opened and when the switch 45-1 is closed, the winding 4B is connected between the terminals of the direct-current machine 5. This circuit extends from conductor 51 through switch 45-1, field-magnet winding 4B, regulating resistor 52 and the operating coil of a field-current relay 57 to the conductor 3 of the direct-current system. The field-magnet winding 4B is thereupon 110 energized from the direct-current machine 5 and causes the alternating-current machine 4 to come into synchronism and to operate as a synchronous motor.

A time-delay transfer and voltage relay 53 115 is connected through a resistor 54 to the secondary winding of a potential transformer 55, the primary winding of which is connected across one phase of the alternating-current circuit 1. Relay 53 is provided with switches 120 53-1 and 53-2 (circuits K and V-21, respectively). The switches 53-1 and 53-2 are adapted to be maintained open as long as the voltage impressed upon the operating coil of the relay 53 exceeds a predetermined value, such as a value corresponding to 70% of normal voltage on the alternating-current circuit 1. When the auxiliary switch 45-4 of the contactor 45 is closed, due to the actuation 125 of the contactor to its closed position, the op-

erating coil of the relay 53 is close-circuited through the switch 45-4 and an auxiliary switch 9-2 of the running circuit interrupter 9, that is closed when the interrupter 9 is open. Since the circuit interrupter 9 is open when the switch 45-4 is closed, switches 53-1 and 53-2 are permitted to close. Closing of switch 53-2 (circuit V-21) is ineffective at this time because switch 35-4 which is connected in series therewith is open, due to the energization of the master control relay 35. The closing of the switch 53-1 (circuit K) is effective, however, to complete an energizing circuit for the operating coil of the transfer relay 43. This circuit extends from the control conductor 2A through the coil of relay 43, a switch 57-1 of the field-current relay 57 (Fig. 1) and switch 53-1 to the conductor 3 of the direct-current circuit.

The field-current relay 57 is adapted to close its switch 57-1 as soon as the field-magnet winding 4B is traversed by exciting current of a predetermined value such as, for instance, three-fourths of the normal exciting current. Thus the relay 57 closes its switch 57-1 very soon after the contactor switch 45-1 is closed to connect the field-magnet winding 4B between the terminals of the direct-current machine 5.

Thus the operating coil of the transfer relay 43 (circuit K) is energized as soon as the alternating-current machine 4 has begun to operate as a synchronous motor and the current traversing its field-magnet winding has attained a predetermined value. When the operating coil of the transfer relay 43 is energized, this relay opens its switch 43-1 (circuit F), which has been previously described, and closes switches 43-2 (circuit I), 43-3 (circuit L) and 43-4 (circuit M-1). The switch 43-3 completes a holding circuit for the operating coil of the relay 43 to maintain energization of the coil of this relay as long as the control conductor 2A is energized from the conductor 2 of the direct-current system.

When the switch 43-2 is closed, a circuit is completed for energizing a tripping coil 7B (circuit I) for the starting circuit interrupter 7. The circuit extends from the conductor 2 of the direct-current system through switch 43-2, tripping coil 7B and an auxiliary switch 7-2 to conductor 3 of the direct-current system. As soon as the tripping coil 7B is energized, the starting circuit interrupter 7 is opened to disconnect the alternating-current machine 4 from the auto-transformer 8 and to disconnect the auto-transformer 8 from the alternating-current circuit 1. When the circuit interrupter 7 opens, its auxiliary switch 7-2 (circuit I) is opened to deenergize the tripping coil 7B.

When the circuit interrupter 7 is opened, an auxiliary switch 7-3, (circuit L) closes to complete a circuit for energizing the operating coil of the running circuit interrupter

control relay 56. This circuit extends from control conductor 2A through the switch 7-3, the coil of the relay 56, an auxiliary switch 9-3 of the running circuit interrupter 9, switch 44-2 of the cut-off relay 44, which is now de-energized, and switch 43-3 of the transfer relay 43 to the conductor 3 of the direct-current system. The relay 56 thereupon opens its switch 56-1 (circuit G-1) and closes switches 56-2 (circuit L) and 56-3 (circuit M). The switch 56-2 is connected in parallel relation to the auxiliary switch 9-3 of the circuit interrupter 9 and serves to maintain a holding circuit for the operating coil of the relay 56 after the circuit interrupter 9 is closed.

When the switch 56-3 is closed, a circuit is completed for energizing the closing coil 9A (circuit M) of the running circuit interrupter 9. The armature windings 4A of the alternating-current machine 4 are thereupon energized directly from the alternating-current circuit 1. At the same time that the closing coil 9A is energized the time-delay cut-off relay 44 is again energized. The energizing circuit of this relay now extends from the conductor 2 of the direct-current circuit through the switch 56-3 (circuit M) of the control relay 56 which has been previously described, the switch 43-4 (circuit M-1) of the transfer relay 43 which has also been described, a conductor 98, and the coil of the relay 44 (circuit G-1) to the conductor 3 of the direct-current circuit. The switch 56-1 (circuit G-1) of the control relay 56 is now open and serves to preclude energization of the closing coil 7A of the starting circuit interrupter 7 at this time.

When a predetermined interval of time has elapsed after the operating coil of the time-delay cut-off relay 44 is energized, this relay opens its switches 44-1 (circuit F) and 44-2 (circuit L) and closes its switch 44-3 (circuit J). The opening of the switch 44-1 (circuit F) is now ineffective since this circuit is already open because the switch 43-1 of the transfer relay 43 is open. The closing of the switch 44-3 is also ineffective at this time and its function will be described later. The opening of the switch 44-2 (circuit L) is effective, however, to interrupt the energizing circuit of the control relay 56. This relay thereupon opens its switches 56-2 (circuit L) and 56-3 (circuit M) and closes its switch 56-1 (circuit G-1). The opening of the switch 56-2 interrupts the holding circuit of the operating coil of the relay 56 (circuit L) and the opening of the switch 56-3 interrupts the energizing circuits for the closing coil 9A (circuit M) of the running circuit interrupter 9 and the operating coil of the cut-off relay 44 (circuit G-1).

During the time required for the relay 44 to operate the circuit interrupter 9 was closed and latched closed so that energiza-

tion of its closing coil 9A is no longer required. From the above description it will be seen that I utilize only one time-delay cut-off relay for effecting de-energization of the closing coils of two individually operated circuit interrupters within the proper time interval after each coil is energized.

When the circuit interrupter 9 is closed to connect the armature windings 4A of the alternating-current machine 4 directly to the circuit 1, the machine 4 begins to operate normally as a synchronous motor and is ready to drive the direct current machine 5 as a generator to supply energy to the direct-current system. The method of connecting the machine 5 to its circuit to supply energy thereto will now be described.

The circuit interrupter 9, in closing, opens auxiliary switches 9-1 (circuit B-5), 9-2 (Fig. 1), 9-3 (circuit L), 9-4 (circuit B54) and 9-5 (circuit X), and closes auxiliary switches 9-6 (circuit B-4), 9-7 (circuit B-54), 9-8 (circuit J), 9-9 (circuit O) and 9-10 (circuit S). Opening of switch 9-1 is ineffective because the switch 35-2 (circuit B-54) maintains a holding circuit for the operating coil of the relay 35 (circuit B). Opening of the switch 9-2 (Fig. 1) interrupts the short-circuit between the terminals of the relay 53 and permits this relay to become operative, as will be described later. Opening of the switch 9-3 (circuit L) precludes re-energization of the operating coil of the control relay 56 when the relay 44 returns to its de-energized position to close its switch 44-2. The function of the remaining auxiliary switches of the circuit interrupter 9 will be apparent at later points in the sequence of operation of the system.

When the auxiliary control relay 40 (circuit E) was energized in response to the closing of the switch 34-3 (circuit C) of the auxiliary master relay 34 (circuit D), as previously described, the relay 40 closed, in addition to switch 40-1 (circuit F), which has been described, two switches 40-2 and 40-3, which are illustrated in Fig. 2 between a direct-current voltage regulator 58 and a reversible rheostat-operating motor 60. The motor 60 is also adapted to be connected to an alternating-current frequency regulator 61 through two switches 62-1 and 62-2 of an inversion auxiliary control relay 62 (circuit V-2) which will be described later. At this point in the sequence the operating coil of the relay 62 is de-energized to permit the switches 62-1 and 62-2 to remain open. The motor 60 is therefore controlled only by the direct-current voltage regulator 58 through the switches 40-2 and 40-3, and is disconnected from the frequency regulator 61.

The direct-current voltage regulator 58 is preferably of the type shown and described in my co-pending application for voltage regulator systems, Serial No. 584,613,

filed August 28, 1922, and assigned to the Westinghouse Electric and Manufacturing Company. This regulator comprises three elements, 58A, 58B and 58C, each of which is provided with a balance-arm and a pair of contact members at each end thereof that are adapted to be engaged selectively, depending upon which way the balance-arm is tilted.

The element 58A is a voltage-balancing element comprising two opposing coils which act upon core members secured to the respective extremities of the balance-arm. The left-hand coil is connected between the conductors 2 and 3 of the main direct-current circuit and the right-hand coil is connected between the conductors 3 and 51, or, in other words, between the terminals of the direct-current machine 5. The two coils of the element 58A are of equal numbers of ampere-turns and are so disposed that, when equal voltages are applied thereto, they exert equal forces upon their respective core members, with the result that the balance-arm of this element is in equilibrium. When the voltage between the conductors 2 and 3 of the direct-current circuit is greater than that of the machine 5, however, the left-hand coil of the element 58A overbalances the right-hand coil, thereby tilting the balance-arm to close the right-hand contact members of this element, and vice versa. The element 58A is also provided with two auxiliary switches 58L and 58R, the purpose and circuit connections of which will be hereinafter described. These switches are closed selectively, depending upon which way the balance-arm of this element of the regulator is tilted.

The element 58B of the voltage regulator 58 is a voltage-regulating element comprising a single coil connected between the conductors 2 and 3 of the direct-current circuit and acting upon a core member that is secured to the left-hand end of the balance-arm of this element. A tension spring acts upon the opposite end of the balance-arm and is so calibrated that, when the voltage impressed upon the coil of this element is less than the normal voltage desired between the conductors 2 and 3 of the direct-current circuit, the spring exerts a greater force on the balance-arm than does the coil, thereby tilting the balance-arm to close the left-hand contacts of this element. Similarly, when the voltage between the conductors 2 and 3 is greater than that which is desired, the force of the coil is greater than that of the spring, and the balance-arm is tilted to close the right-hand contact members.

The third element 58C of the voltage regulator 58 is a current-regulating element which is similar in structure to the voltage-regulating element 58B. The coil of this element is connected in parallel relation to the interpole field-magnet winding 10 of the ma-

chine 5. Since the winding 10 is connected in series with the armature windings of the machine 5, the voltage between the terminals thereof is directly proportional to the amount of current traversing the armature windings. Thus, it will be seen that, when this current exceeds a predetermined value, the force exerted by the coil of the current-regulating element 58C is greater than that exerted by the spring of this element, and, therefore, the balance-arm is tilted to close the right-hand contact members. Conversely, when the current is less than the predetermined value, the balance-arm is tilted in the opposite direction to close the left-hand contact members of this element. The coil and spring are so calibrated and arranged that this predetermined value of current is the maximum desirable value to be permitted to traverse the armature windings of the machine 5.

As soon as the relay 40 closes its switches 40-2 and 40-3, the direct-current voltage regulator 58 begins to control the operation of the rheostat-operating motor 60. The first operation of the voltage regulator 58 is to balance the voltage of the machine 5 with the voltage of the direct-current circuit. This is accomplished by the voltage-balancing element 58A, which is effective by reason of the fact that the direct-current circuit interrupter 21 has not yet been closed, and an auxiliary switch 21-7 thereof, that is closed when the circuit interrupter 21 is open, is connected in series in the circuit extending from the upper terminal of the machine 5 through the conductor 51 to the balance-arm of the element 58A. The voltage-regulating element 58B and the current-regulating element 58C of the regulator 58 are ineffective until the circuit interrupter 21 is closed, by reason of the fact that the circuit extending to the balance-arms thereof includes an auxiliary switch 21-8 of the circuit interrupter 21 that is closed only when that circuit interrupter is closed.

As has been explained previously, the voltage-balancing element 58A closes its right-hand contact members when the voltage between the conductors 2 and 3 of the direct-current circuit is greater than that of the machine 5, and closes its left-hand contact members when the voltage of the machine 5 is greater than that between the conductors 2 and 3. Therefore, until the voltage of the machine 5 has built up to a value equal to that of the direct-current circuit, the right-hand contact members of the element 58A are closed to connect the armature member and the right-hand field-magnet winding of the reversible rheostat-operating motor 60 in series between the terminals of the machine 5. This circuit extends from the upper terminal of the machine 5, through the conductor 51, switch 21-7, balance-arm and right-hand contact members of voltage-balancing

element 58A, switch 40-2, right-hand field magnet winding and armature member of motor 60, and conductor 3 to the lower terminal of machine 5. The right-hand field-magnet winding of motor 60 is so disposed with respect to the armature member that, when the motor is energized in this way, it turns in a direction to decrease the effectiveness of a resistor 63 that is connected in circuit with the shunt field-magnet winding 5-A of the machine 5. The excitation of the machine 5 is, therefore, increased to increase its voltage until this voltage equals that between the conductors 2 and 3 of the direct-current circuit.

If the voltage of the machine 5 is built up to a value exceeding that of the direct-current circuit, the balance-arm of the voltage-balancing element 58A is tilted in the opposite direction to open the right-hand contact members and to close the left-hand contact members of this element. The motor 60 is then energized by a circuit extending from the upper terminal of the machine 5 through conductor 51, switch 21-7, balance-arm and left-hand contact members of element 58A, switch 40-3, left-hand field-magnet winding and armature member of motor 60, and conductor 3 to the lower terminal of machine 5. The left-hand field-magnet winding of motor 60 is so disposed with respect to the armature member that, when the motor is energized in this way, it turns in a direction to increase the effectiveness of the resistor 63, thereby decreasing the voltage generated by the machine 5. Thus, it will be seen that the voltage-balancing element 58A controls the motor 60 to vary the effectiveness of the resistor 63 until the voltage of the machine 5 is exactly equal to that of the direct-current circuit.

Until this balanced condition is attained, the two auxiliary switches 58-R and 58-L of the voltage-balancing element 58A, the circuit connections of which are shown in circuit P, are alternately closed to energize the operating coil of a time-delay relay 64 (circuit P). This relay is provided with a switch 64-1 (circuit S) that is adapted to be closed after the operating coil of the relay 64 has been de-energized for a predetermined interval of time. In other words, this relay is adapted to actuate its switch 64-1 to its full open position instantaneously whenever its operating coil is energized for an instant, but permits the switch 64-1 to be closed only when the operating coil 64 has been deenergized continuously for a predetermined interval of time. Thus the auxiliary switches 58-R and 58-L prevent closing of the switch 64-1 while the voltage-balancing element 58A is operating either to raise or to lower the voltage of the machine 5, and permit closing of this switch only after the voltage of the machine 5 has been balanced with the voltage

of the direct current circuit for a predetermined interval of time.

An auxiliary switch 7-4 of the starting circuit interrupter 7 that is closed when the interrupter 7 is closed, and a switch 57-2 of the field-current relay 57 that is closed when the relay 57 is not energized to a predetermined degree, are each connected in parallel relation to the switches 58-R and 58-L (circuit P). These switches preclude de-energization of the operating coil of the relay 64 and consequent closing of the switch 64-1 while the starting interrupter 7 is closed and while the current traversing the field-magnet winding 4B of the machine 4 is below a predetermined value, respectively.

Thus when the circuit interrupter 7 is open, the current traversing the field-magnet winding 4B is above a predetermined value, and the voltage of the machine 5 has been balanced with that of the direct-current circuit for a predetermined interval of time, the switch 64-1 (circuit S) is permitted to close. The switch 64-1 co-operates with certain other switches which are about to be described to connect the operating coil of a direct-current circuit interrupter control relay 65 (circuit S) between the terminals of the machine 5.

A polarized relay 66 (circuit Q) is connected directly across the terminals of the direct-current machine 5 and is adapted to close a switch 66-1 (circuit R) when the voltage of the machine 5 builds up with the correct polarity relative to the polarity of the direct-current circuit. This relay affords protection against the remote possibility of the machine 5 being connected to the direct-current circuit with its polarity reversed. When the switch 66-1 is closed, a voltage-responsive relay 67 (circuit R) is connected between the terminals of the machine 5. The circuit of the operating coil of the relay 67 extends through the switch 39-1 (circuit S) of the control relay 39 which has been previously described.

If the voltage of the machine 5 is above a predetermined value, such as, for example, 85% of normal voltage, the relay 67 effects closing of its switch 67-1 (circuit S). The operating coil of the relay 65 (circuit S) is now energized from the machine 5 through the circuit extending from the conductor 51, through the auxiliary switch 9-10 of the running circuit interrupter 9, an auxiliary switch 21-1 of the direct-current circuit interrupter 21 (Fig. 2), a switch 68-1 of a time-delay cut-off relay 68 (circuit T-1), switch 64-1 of the time delay relay 64, switch 67-1 of the voltage-responsive relay 67, and switch 39-1 of the control relay 39 to the conductor 3 of the direct-current circuit. The relay 65 thereupon closes its two switches 65-1 and 65-2 (circuits S and T,

respectively). The switch 65-1 so shunts the auxiliary switch 21-1 (circuit S) of the circuit interrupter 21 as to maintain energization of the operating coil of the relay 65 after the interrupter 21 is closed. The switch 65-2 completes a circuit for energizing the closing coil 21A (circuit T) of the circuit interrupter 21, and for energizing the operating coil of the time-delay cut-off relay 68 (circuit T-1).

The circuit interrupter 21 is closed in response to the energization of its closing coil 21A, and is latched in its closed position. The cut-off relay 68 opens its switch 68-1 (circuit S) after a predetermined interval of time to de-energize the operating coil of the control relay 65. The switches 65-1 and 65-2 are then permitted to open. Opening of the switch 65-1 interrupts the holding circuit for the operating coil of the relay 65 (circuit S) and opening of the switch 65-2 interrupts the energizing circuit for the closing coil 21A (circuit T) of the interrupter 21 and for the operating coil of the cut-off relay 68 (circuit T-1). The interrupter 21 is now latched in its closed position and all of its controlling apparatus is de-energized.

The operation of starting and connecting the machines 4 and 5 to their respective circuits to translate alternating-current energy into direct-current energy under normal condition is now completed. The machines continue to operate in this manner as long as there is a sufficient demand for energy upon the direct-current circuit. During such operation the direct-current voltage regulator 58 operates to regulate the voltage of and load on the direct-current machine 5. This operation consists in permitting the machine 5 to assume a certain load, and as long as the load demand upon the machine is below this value the voltage-regulating element 58B maintains the voltage of the machine at its normal value. When the load demand exceeds the predetermined value, however, the current-regulating element 58C operates to maintain the current output of the machine at the maximum permissible value, and to vary its voltage in accordance therewith.

When the circuit interrupter 21 was closed, its auxiliary switch 21-7 was opened to disconnect the balance-arm of the voltage-balancing element 58A from the conductor 51, and the auxiliary switch 21-8 was closed to connect the balance-arm of the current-regulating element 58C to the conductor 51. The element 58A was thus rendered ineffective, and the elements 58B and 58C were rendered effective upon closing of the circuit interrupter 21. As previously set forth, when the current traversing the machine 5 is less than the maximum desired value, the left-hand contact members of the current-regulating element 58C remain closed. These contact mem-

bers, when closed, complete a circuit extending from the conductor 51 through the switch 21—8, the balance-arm of the current-regulating element 58C and said contact members 5 to the balance-arm of the voltage-regulating element 58B, thereby rendering this element effective to maintain the voltage between the conductors 2 and 3 of the direct-current circuit at the predetermined desired value.

10 The voltage-regulating element 58B is effective in the manner set forth by reason of the fact that it closes its left-hand contact members when the voltage between the conductors 2 and 3 is below the desired value, 15 thereby completing a circuit for energizing the rheostat-operating motor 60. This circuit extends from the upper terminal of the machine 5, through the conductor 51, switch 21—8, balance-arm and left-hand contact members of current-regulating element 58C, balance-arm and left-hand contact members of voltage-regulating element 58B, switch 20 40—2, right-hand field-magnet winding and armature member of motor 60 and conductor 25 3 to the lower terminal of the machine 5. The motor 60, therefore, operates in such direction as to decrease the effectiveness of the resistor 63, thereby increasing the excitation 30 of the machine 5. The voltage generated by the machine 5 is thus increased to raise the voltage impressed upon the conductors 2 and 3 to the desired value. If this voltage rises above the desired value, the element 58B closes its right-hand contact members to complete 35 a circuit extending through the switch 40—3 and left-hand field-magnet winding and armature member of the motor 60. The motor 60, therefore, operates in such direction as to increase the effectiveness of the resistor 63, thereby reducing the excitation, 40 and, consequently, the voltage, of the machine 5 to the desired value. Thus, it will be seen that, while the machine 5 is connected to the direct-current circuit through the circuit interrupter 21, and the current traversing the machine is below the maximum desired value, the voltage-regulating element 58B is operative to maintain the voltage between the conductors 2 and 3 at the predetermined desired value by suitably controlling 45 the energization of the motor 60 to vary the excitation of the machine 5.

If the current traversing the machine 5 exceeds the maximum desired value, the current-regulating element 58C opens its left-hand contact members and closes its right-hand contact members. The opening of its left-hand contact members interrupts the circuit extending to the balance-arm of the voltage-regulating element 58B, which was previously described, and thereby renders the element 58B ineffective to control the energization of the motor 60. The closing of the right-hand contact members of the element

58C completes a circuit for energizing the 65 motor 60 through its left-hand field-magnet winding to cause the voltage of the machine 5 to be reduced in the same manner as previously described. This circuit extends from the upper terminal of the machine 5, through 70 the conductor 51, switch 21—8, balance-arm and right-hand contact members of element 58C, switch 40—3, left-hand field-magnet winding and armature member of motor 60, and conductor 3 to the lower terminal of the 75 machine 5. The voltage of the machine 5 is thus immediately reduced until the current traversing the same is decreased to the maximum desirable value, and the current-regulating element 58C continues to regulate the 80 voltage of the machine 5 as long as the load demand thereon is so great that normal voltage would cause an excessive current traversal thereof. As soon as this condition ceases to exist, the voltage-regulating element 85 58B is again rendered effective to maintain the voltage of the direct-current circuit at its normal value.

When the load demand upon the machine 5 falls and remains below a predetermined 90 value for a predetermined interval of time, it is desired that the operation of the machines 4 and 5 be stopped. This is accomplished by means of an alternating-current under-load relay 69 (Fig. 1) and the time-delay relay 30 (circuit B). In addition to its main operating coil or motor, this relay comprises an auxiliary or clutch coil 30A that permits the relay to actuate a plurality of switches with different time settings. The 100 structure and method of operation of this relay is fully set forth in the co-pending application of Charles A. Butcher and Lloyd F. Hunt for time limit relays, Serial No. 716,354, filed May 28, 1924, and assigned to 105 the Westinghouse Electric and Manufacturing Company.

The operating coil of the under-load relay 69 is connected in series with one of a plurality of current transformers 77 (Fig. 1) so that 110 its energization is proportional to the value of current that is traversing the armature windings 4A of the machine 4. When this current falls below a predetermined value the relay 69 closes its switch 69—1 (circuit 115 B—4) to energize the motor 30 (circuit B) and clutch coil 30A (circuit B—3) of the time-delay relay. The energizing circuit for the motor 30 extends from the conductor 2 of the direct-current circuit through the switch 31—1 of the over-speed device 31, switch 32—1 of the lock-out relay 32, motor winding 30, switch 33—1 of the alternating-current thermal relay 33, conductor 70, switch 69—1 of the under-load relay 69, and auxiliary 120 switch 9—6 of the running circuit interrupter 9 that is closed when the interrupter 9 is closed, to the conductor 3 of the direct-current circuit.

rent circuit. The energizing circuit for the clutch coil 30A extends from the conductor 2, through switches 31-1 and 32-1, coil 30A, switch 35-1 of the master control relay 35, and switches 69-1 and 9-3 to conductor 3.

Since the clutch coil 30A is now energized the switch 30-1 is not closed, but switches 30-2 (circuit B-52) and 30-3 (circuit C-5) are actuated toward their respective closed positions. The time setting of the switch 30-3 is considerably less than that of the switch 30-2 but its closing at this time is ineffective, as will be described later. If the load demand on the machine 4 increases to a value greater than the value at which the underload relay 69 is adjusted to close its switch 69-1 before the time-delay relay 30 has closed its switch 30-2, this switch is permitted to return immediately to its open position. Thus the condition of under-load must persist continuously for the time interval for which the switch 30-2 is adjusted to operate in order to effect automatic disconnection of the machines 4 and 5 from their circuits.

When the switch 30-2 is closed in response to this condition the operating coil of the master control relay 35 (circuit B-5) is short-circuited thereby, and the switches 35-1 (circuit B-3), 35-2 (circuit B54), and 35-3 (circuit D) are permitted to open and the switch 35-4 (circuit V-21) is permitted to close. The function of the switch 35-4 will be described later. Opening of the switch 35-1 de-energizes the clutch coil 30A of the time delay relay (circuit B-3) and permits the switch 30-2 to return to its original position. Opening of the switch 35-2 interrupts the holding circuit for the operating coil of the master relay 35, and precludes immediate re-energization thereof when the short-circuit between its terminals is removed due to the opening of the switch 30-2. Opening of the switch 35-3 interrupts the energizing circuit for the operating coil of the auxiliary master control relay 34 (circuit D) and permits this relay to open its switches 34-3 (circuit C) and 34-4 (circuit AA) and to close its switches 34-1 (circuit B) and 34-2 (circuit B-52). The operating coil of the control relay 39 (circuit D-1) is also de-energized when the switch 35-3 is opened, and this relay thereupon opens its switch 39-1 (circuit S) and closes its switch 39-2 (circuit O).

The control conductor 2A is not immediately disconnected from the conductor 2 when the switch 34-3 (circuit C) is opened, for their switch is shunted by an auxiliary switch 21-2 of the direct-current circuit interrupter 21 that is closed when the interrupter 21 is closed. Thus the conductor 2A is energized from the conductor 2 as long as the circuit interrupter 21 is closed. The interrupter 21 is opened in response to the opening of the

switch 39-1 (circuit S), because a no-volt-⁶⁵ age tripping coil 21C (circuit S-1) of the interrupter 21 is de-energized thereby.

When the interrupter 21 opens the auxiliary switch 21-2 (circuit C) also opens to disconnect the conductor 2A from the conductor 2 and thereby to de-energize all of the control apparatus that is connected to the conductor 2A. This includes a no-voltage tripping coil 9-C (circuit N) of the running circuit interrupter 9, which causes the interrupter 9 to open to disconnect the machine 4 from the circuit 1. The energization of the conductor 2A through the auxiliary switch 21-2 until the interrupter 21 opens insures the disconnection of the machine 5 from the direct-current circuit prior to the disconnection of the machine 4 from the alternating-current circuit, thereby precluding a reversal in the direction of the flow of energy between the circuits.

As the machines gradually come to rest, the voltage generated by the machine 5 decreases gradually to zero and the control apparatus that were energized therefrom return to their de-energized positions. All of the apparatus in the station is now in the same condition that was originally assumed, and is again ready to respond to similar conditions in the same manner as described above.

The operation of the machines may be stopped automatically in response to predetermined conditions other than a condition of under-load in the manner described above. Various protective devices such as the alternating-current thermal relay 33 (Fig. 1) and a phase-balance current relay 71 (Fig. 1) may be provided with switches such as 33-2 (circuit B-51) and 71-1 (circuit B-54), respectively, that short-circuit the operating coil of the master relay 35 (circuit B-5) to stop the operation of the machines in the same manner that they are stopped in response to the closing of the switch 30-2 (circuit B-52) in response to sustained under-load. The switch 71-1 is connected in series with an auxiliary switch 9-7 (circuit B-54) between the terminals of the master relay 35 so that unbalanced currents in the several phases of the armature windings 4A of the machine 4 cause the coil of the relay 35 to be short-circuited only when the running circuit interrupter 9 is closed.

If such an unbalanced condition occurs while the machine 4 is being started, it is an indication of internal trouble in the machine, and it is desired that the machine be locked out of service until an inspection thereof has been made. This is accomplished by means of the lock-out relay 32 (circuit C). If the phase-balance relay 71 closes its switch while the machine is starting, short-circuiting of the operating coil of the master relay 35 (circuit B-5) is precluded because the auxiliary

switch 9-7 (circuit B-54) is open, but since another auxiliary switch 9-4 (circuit C-2) of the running circuit interrupter 9 is closed, the operating coil of the lock-out relay 32 (circuit C) is energized.

The circuit for energizing the relay 32 extends from conductor 2 of the direct-current circuit through switch 34-3 (circuit C) of the auxiliary master relay 34, a closed switch 72-1 of a relay 72 (circuit V-22) to be described later, coil of relay 32, switch 9-4 (circuit C-2), and switches 71-1 and 35-2 (circuit B-54) to conductor 3. The relay 32 thereupon opens its switches 32-1 (circuit B) and 32-2 (circuit B-5) which latch in their open positions and so remain until they are reset manually by an attendant. The switches 32-1 and 32-2 open the circuits of the time-delay relay 30 (circuit B) and the master relay 35 (circuit B-5) and thereby entirely preclude further operation of the machines in the station until the relay 32 is reset.

Other relays such as a direct-current thermal relay 73 (Fig. 2), and an alternating-current short-circuit relay 74 (Fig. 1) may be provided with switches such as 73-1 (circuit C-3) and 74-1 (circuit C-4) which are also adapted to energize the lock-out relay 32 when they are closed in response to predetermined abnormal conditions. The switch 30-3 (circuit C-5) of the time-delay relay 30 is connected in series with an auxiliary switch 7-5 of the starting circuit interrupter 7 so that if the switch 30-3 is closed while the interrupter 7 is closed, the lock-out relay 32 will be energized. This affords protection against the machine 4 running for an abnormal length of time on the starting connections, which is an indication of trouble, within the station.

This protection is obtained by providing an auxiliary switch 7-6 (circuit B-3) of the interrupter 7, that causes the motor winding 30 and the clutch winding 30A of the time-delay relay to be energized as soon as the interrupter 7 is closed. If the transfer from starting to running connections is effected within a normal period of time, the interrupter 7 will be opened before the switch 30-3 is closed. The coils of the relay 30 are then de-energized because of the opening of the auxiliary switch 7-6 (circuit B-3) and that relay returns to its original position. If the interrupter 7 remains closed for an abnormal length of time, such as two minutes, however, the switch 30-3 (circuit C-5) is closed and causes the apparatus to be locked out of service as described above. When the apparatus is locked out during the starting period of the machine 4 the starting circuit interrupter 7 is tripped by a no-voltage trip coil 7C (circuit H) that is de-energized when the conductor 2A is disconnected from the conductor 2 by the opening of the switch

34-3 (circuit C) of the auxiliary master relay 34.

From the above description it is seen that the apparatus may be automatically stopped and disconnected from the power circuits in two ways, viz., in response to the sustained underload, or in response to the functioning of any one of a variety of protective devices. The protective devices may be divided into two classes, namely, those which are responsive to temporary abnormal conditions, and those which are responsive to permanent faults. Occurrence of temporary abnormal conditions will cause the apparatus to be stopped, but will permit re-starting thereof when conditions again become normal. Occurrence of a permanent fault, however, will cause the apparatus to be stopped immediately and will preclude re-starting thereof until the station has been visited by an attendant who resets the lock-out relay after remedying the fault which caused the operation thereof.

The apparatus in the station may also be manually stopped from the control station 23 (Fig. 1). If it is desired to stop the apparatus immediately at any time, but to permit automatic re-starting, thereof, the push-button 24 is depressed. This connects the control conductor 28 directly to the conductor 2 of the direct-current circuit, which causes the operating coil of the stopping relay 36 (circuit AA) to be energized. The energizing circuit for this relay may be traced from conductor 2 of the direct-current circuit, through switch 24 in the control station, conductor 28, coil of relay 36, and switch 34-4 of auxiliary master relay 34, to conductor 3.

When the coil of the relay 36 is energized, this relay opens its switches 36-1 (circuit B-5) and 36-2 (circuit AA-3) and closes its switch 36-3 (circuit AA). The latter switch so shunts the switch 34-4 (circuit AA) as to maintain energization of the operating coil of the relay 36 after the relay 34 opens its switch 34-4, as long as the push-button switch 24 is kept depressed. The switch 36-1 (circuit B-5) opens the circuit of the master relay 35 and thereby causes the operation of the machines to stop, as previously described. The opening of the switch 36-2 (circuit AA-3) prevents the establishment of a short-circuit between the conductors 2 and 3 of the direct-current circuit, which otherwise might occur under certain conditions.

As soon as the switch 24 is released, the circuit of the coil of the relay 36 (circuit AA) is broken, so that this relay again opens its switch 36-3 (circuit AA) and closes its switches 36-1 (circuit B-5) and 36-2 (circuit AA-3). Automatic or manual starting of the apparatus may now take place at any time. If it is desired to preclude re-starting of the apparatus the knife-switch 26 at the

control station 23 is thrown to its upper position. If the apparatus is operating normally to take energy from the alternating-current circuit and to supply energy to the direct-current circuit, the normal auxiliary master control relay 34 (circuit D) will be energized, and its switch 34-4 (circuit AA) will be closed. The operating coil of the stopping relay 36 (circuit AA) will then be energized as previously described and its switch 36-3 will maintain a holding circuit therefor as long as the switch 26 is closed in its upper position and operation of the apparatus will be precluded because the switch 36-1 (circuit B-5) will be maintained open.

Likewise, if the apparatus is operating in the inverted manner, so-called, to take energy from the direct-current circuit and to supply energy to the alternating-current circuit, a switch 72-2 (circuit AA) of the auxiliary inversion relay 72 (circuit V-22), which will be described later, will be closed. The switch 72-2 shunts the switches 34-4 and 36-3 (circuit AA) and the operating coil of the stopping relay 36 is energized in the same manner as though the switch 34-4 were closed.

If the switch 26 is closed in its upper position while the machines 4 and 5 are not operating, the switches 34-4, 36-3, and 72-2 (circuit AA) will all be open, and the coil of the stopping relay 36 will not be energized until the apparatus attempts to start either normally or inverted. When such an attempt to start is made, either the switch 34-4 or 72-2 will be closed, and the stopping relay 36 will then function as before to preclude operation of the apparatus until the switch 26 has been moved from its upper position and either a manual or an automatic starting indication has been given.

The apparatus may be started manually from the control station 23 by closing the push-button switch 25, provided the switch 26 is closed in its lower position and starting is not precluded by any abnormal conditions in the power station. The circuit for manual starting extends from the conductor 3 of the direct-current circuit, through the push-button switch 25 and the knife switch 26 in its lower position at the control station 23, over the control conductor 28, through a resistor 75 and switch 36-2 (circuit AA-3) through a switch 76-1 (circuit B-52) of an inversion starting control relay 76 (circuit V-21) to be described later, through a switch 34-2 (circuit B-52) of the normal auxiliary master control relay 34 (circuit D), through the operating coil of the normal master control relay 35 (circuit B-5), and thence through resistor 37 and switches 36-1, 32-2, 32-1 and 31-1 (circuits B-5 and B), as previously described for automatic starting, to the conductor 2 of the direct-current circuit. The operating coil of the normal

master control relay 35 is thus energized from the direct-current circuit, and the remainder of the automatic control apparatus functions as previously described to start the machines 4 and 5 and to connect them to their respective power circuits.

The control conductor 28 has one other function, namely, to energize the indicating device 27 in the control station 23, to indicate whether or not the machines in the power station are operating. When the circuit interrupter 21 is closed to connect the machine 5 to the direct-current circuit, an auxiliary switch 21-3 (circuit AA-1) is closed to connect a resistor 78 in series with the indicating device 27 across the direct-current circuit. This circuit extends from the conductor 2 of the direct-current circuit, through a resistor 99 and the indicating device 27 (Fig. 1) over the control conductor 28, and through the resistor 78 and switch 21-3 (circuit AA-1) to the conductor 3 of the direct-current circuit. The device 27 may be either an ammeter or a voltmeter, properly calibrated, and when it is traversed by current of a predetermined value, depending upon the predetermined resistance of the circuit described above, its pointer will assume a predetermined position which will correspond to a mark on the dial indicating that one power unit is connected between the power circuits in the main station.

Where there are more power units than one in the main station, additional circuits such as AA-2 will be provided in parallel relation to the circuit AA-1. Each additional circuit of this sort will comprise a resistor, such as 178, and an auxiliary switch, such as 121-3, of the main direct-current circuit interrupter of the corresponding unit. Thus, as each additional unit goes into service, another resistor will automatically be connected in parallel relation to the resistor 78, thereby decreasing the total resistance of the circuit of the indicating device 27. In other words, the resistance of that circuit is varied according to the number of units operating, and since the deflection of the indicating device 27 varies according to the current traversing, and hence the resistance of its circuit, this device will indicate just how many units are operatively connected to the direct-current circuit.

The foregoing description covers in detail the various features of operation of the system embodying my invention, assuming that energy is available at all times from the alternating-current circuit 1. As stated before, however, if the voltage of the circuit 1 should fail it is desired that the direct-current machine 5 shall operate as a motor to drive the alternating-current machine 4 as a generator to supply energy to the circuit 1. This gives rise to the consideration of four more possible operating conditions, namely, (1) failure of both alternating-current and direct-current

voltages while the machines are operating normally; (2) failure of both alternating-current and direct-current voltages while the machines are not operating; (3) failure of 5 alternating-current voltage only while the machines are operating; and (4) failure of alternating-current voltage only while the machines are not operating.

Under condition (1) the machines will 10 come to a stand-still, which is then the same as condition (2). If the direct-current voltage is restored before the alternating-current voltage, which then corresponds to condition 15 (4), the machines will start and operate "inverted", that is, to translate energy from the direct-current circuit to the alternating-current circuit, which is the reverse of normal 20 operation. Under condition (3) the machines will continue to operate and the direction of energy traversal thereof will be reversed 25 without stopping and re-starting the machines. Therefore, we have to consider inverted starting and operation of the machines from stand-still, and inversion while the machines are running. These conditions will be described in the order named.

Let us assume any one of conditions (1), 30 (2) and (4), above, when direct-current energy is available at the power station and alternating-current energy is not available, and 35 the machines are not operating. When the alternating-current voltage fails, the relay 53 (Fig. 1) closes its switches 53-1 (circuit K) and 53-2 (circuit V-21). Switch 53-2, 40 when closed, completes a circuit for energizing the operating coils of the inversion starting control relay 76 (circuit V-21) and the inversion auxiliary starting control relay 72 (circuit V-22). This circuit may be traced 45 from the conductor 2 of the direct-current circuit through the switches 31-1, 32-1, 32-2 and 36-1 (circuits B and B-5), which have already been described, over a conductor 79, through a switch 40-4 (circuit V-2) of the normal auxiliary control relay 40 (circuit E) which is now de-energized, thence over two parallel paths, one of which 50 comprises a resistor 80 and the operating coil of the relay 76 (circuit V-21), and the other of which comprises the operating coil of the relay 72 (circuit V-22), and thence through the switch 35-4 of the normal master control relay 35 and the switch 53-2 of the voltage-responsive relay 53 to the conductor 3 of the 55 direct-current circuit.

The relay 76, when energized, opens switch 76-1 (circuit B-52) and closes switches 76-2 (circuit L-1), 76-3 (circuit V-21) and 76-4 (circuit X). The relay 60 72 simultaneously opens switch 72-1 (circuit C) and closes switches 72-2 (circuit AA), 72-3 and 72-4 (circuit B-53), 72-5 (circuit C-1), and 72-6 and 72-7 (circuit D). The switches 76-1, 72-1 and 72-2 65 have already been described. The function

of the remaining switches enumerated above will be described as they become effective in the sequence.

Switch 76-4, when closed, completes a circuit for energizing the operating coil of a 70 direct-current starting contactor control relay 81 (circuit X). This circuit extends from the conductor 2 of the direct-current circuit through an auxiliary switch 9-5 of the alternating-current running circuit interrupter 9, coil of relay 81 and switch 76-4 to the conductor 3 of the direct-current circuit. The relay 81 thereupon closes its switch 81-1 (circuit Y) to connect the closing coil 18A of the direct-current starting contactor 18 (Fig. 2) across the direct-current circuit. The contactor 18 is then closed to connect the upper terminal of the machine 5 to the conductor 2 of the direct-current circuit through the resistors 12, 13 and 14 and 85 the series current relays 15, 16 and 17.

The direct-current machine 5 now receives energy from the direct-current circuit over the circuit just described and begins to operate as a motor. The current traversing the 90 relays 15, 16 and 17 is at first great enough to cause these relays to open their respective switches 15-1 (circuit Z), 16-1 (circuit ZZ) and 17-1 (circuit S). As the speed and 95 hence the counter electro-motive force of the machine 5 increases, however, this current decreases to such a value that the relay 15 is permitted to close its switch 15-1 to cause the closing coil 19A (circuit Z) of the resistance-shunting contactor 19 (Fig. 2) to be 100 energized from the direct-current circuit. The contactor 19 thereupon closes to short-circuit the resistor 12 (Fig. 2).

The speed of the machine 5 now increases 105 further until the current traversing the relay 16 falls to such a value that the switch 16-1 is closed to effect energization of the closing coil 20A (circuit ZZ) of the contactor 20 (Fig. 2). The contactor 20 then closes to 110 short-circuit the operating coil of the relay 15 and the resistor 13 (Fig. 2). As the current traversing the relay 17 decreases to a value which permits this relay to close its switch 17-1 (circuit S), the operating coil 115 of the main direct-current circuit interrupter control relay 65 (circuit S) is energized. The circuit for energizing the relay 65 may be traced in the same manner as described for 120 normal operation of the machines, except that it extends through the switch 17-1 instead of through the switch 9-10. The circuit interrupter 21 is now closed and latched and its closing coil de-energized in the same manner as previously described.

The switch 39-1 (circuit S) of the control 125 relay 39 (circuit D-1) is now closed because the operating coil of this relay was connected across the direct-current circuit by the closing of the switch 72-7 (circuit D) of the relay 72 (circuit V-22) previously mentioned. 130

The switch 72-6 (circuit D) of the same relay closed simultaneously to short-circuit the operating coil of the normal master control relay 34, to preclude energization and actuation thereof. The switch 34-3 (circuit C) did not close, therefore, to connect the conductor 2A to the conductor 2, and connection between the conductors is not effected until the direct-current circuit interrupter 21 is closed to close its auxiliary switch 21-2 (circuit C).

When the machine 5 started to take energy from the direct-circuit through the circuit interrupter 21, current traversed the shunt 22 (Fig. 2) in the reverse of normal direction, to cause a reverse-current relay 82 (Fig. 2) to open a switch 82-1 (circuit V) and to close a switch 82-2 (circuit V). Since the alternating-current reverse-energy relay 48 (Fig. 1) is de-energized because the armature windings 4A of the machine 4 are open-circuited, the switch 48-1 (circuit U) of this relay is closed and the switch 48-2 (circuit U) is open. The operating coil of the relay 49 (circuit U) is therefore de-energized and its switch 49-1 (circuit V) is closed. Thus when the switch 82-2 is closed, the operating coil of the inversion master control relay 41 is completed from conductor 79, through resistor 83, coil of relay 41, and switches 82-2 and 49-1 to conductor 3. The relay 41 thereupon opens its switch 41-1 (circuit E) and closes its switch 41-2 (circuit V).

Opening of the switch 41-1 precludes energization of the operating coil of the normal auxiliary control relay 40 (circuit E) and therefore its switch 40-4 (circuit V-2) remains closed, and its switches 40-1 (circuit F) and 40-2 and 40-3 (Fig. 2) remain open. Since the switch 40-1 is open the operating coil of the relay 42 (circuit F) cannot be energized, the switch 42-2 (circuit G) remains open, and, consequently, the closing coil 7A of the alternating-current circuit interrupter 7 cannot be energized. The running interrupter 9 is closed, however, as will be described presently.

The switch 41-2 of the inversion master relay 41 is connected in parallel relation to the switch 82-2 (circuit V) and maintains a holding circuit for the relay 41 after the switch 82-2 opens. This switch also completes the energizing circuit of an auxiliary relay 84 (circuit V-1) and an inversion auxiliary control relay 62 (circuit V-2). The circuit of the relay 84 extends from conductor 79, through the coil of relay 84, and through switches 41-2 and 49-1 to conductor 3. The relay 84, when energized closes a switch 84-1 (circuit W) to connect the closing coil 85A of a shunting contactor 85 (Fig. 2) across the direct-current circuit. The contactor 85 is thereupon closed to short-circuit the series field-magnet winding 11 of the machine 5 while it is operating as a motor.

The circuit of the inversion auxiliary control relay 62 extends from the conductor 79, through the switch 40-4 (circuit V-2) an auxiliary switch 21-4 (circuit V-2) of the circuit interrupter 21 (Fig. 2), coil of relay 62, and switches 41-2 and 49-1 to conductor 3. The relay 62 closes switches 62-1 and 62-2 (Fig. 2), previously mentioned, and 62-3 and 62-4 (Fig. 1) and opens switches 62-5 and 62-6 (Fig. 1). The function of the switches will be more fully described later.

The switch 76-2 (circuit L-1) of the inversion starting control relay 76 is connected in series with an auxiliary switch 21-5 (circuit L-1) of the circuit interrupter 21 to effect energization of the operating coil of the transfer relay 43 (circuit K) as soon as the interrupter 21 is closed. The alternating-current running circuit interrupter 9 (Fig. 1) is now closed, latched closed, and its closing coil de-energized in the same manner as described for normal starting of the apparatus.

When the interrupter 9 is closed its auxiliary switch 9-8 (circuit J) cooperates with switch 44-3 (circuit J) of the time-delay cut-off relay 44 (circuit G-1), which remains closed for an instant after the interrupter 9 is closed, to effect energization of the closing coil of the contactor 45 (circuit J). This contactor immediately opens its switch 45-2 (Fig. 1) and closes its switches 45-1 (Fig. 1) and 45-3 (circuit J). Switch 45-2 opens the circuit shunting the field-magnet winding 4B of the machine 4 and switch 45-1 connects the winding 4B across the terminals of the machine 5 to be excited from the direct-current circuit. Switch 45-3 so shunts switch 44-3 (circuit J) of the cut-off relay 44 as to maintain energization of the closing coil of the contactor 45 after the switch 44-3 is opened.

Auxiliary switch 9-9 (circuit O) of the interrupter 9 connects the operating coil of an inversion auxiliary master control relay 86 (circuit O-1) across the direct-current circuit when the interrupter 9 is closed. The relay 86 thereupon opens its switch 86-1 (circuit B-53) and closes its switch 86-2 (circuit B-53). Until the interrupter 9 was closed the switch 86-1 co-operated with switch 72-3 (circuit B-53) of the inversion auxiliary starting control relay 72 to short-circuit the operating coil of the normal master control relay 35 (circuit B-5), but this short-circuit is now broken and switch 86-2 co-operates with switch 72-4 (circuit B-53) of the relay 72 to connect the operating coil of the relay 35 across the direct-current circuit. The relay 35 is thus energized and its switch 35-2 (circuit B-54) establishes a holding circuit for maintaining energization of the operating coil after the switch 72-4 is opened.

The relay 35 now actuates its switches in the same manner as previously described. Switch 35-4 (circuit V-21) is opened to permit the relays 76 and 72 to return to their de-energized conditions. Thus the short-circuit around the operating coil of the normal auxiliary master control relay 34 (circuit D) is broken by the opening of the switch 72-6 and the relays 34 and 39 are energized through the switch 35-3 (circuit D) of the normal master control relay 35.

The machines 4 and 5 are now operating in the inverted manner, that is, taking energy from the direct-current circuit and supplying energy to the alternating-current circuit. During inverted operation the alternating-current frequency regulator 61 (Fig. 2) controls the rheostat operating motor 60 through the switches 62-1 and 62-2, this motor being disconnected from the direct-current voltage regulator 58 because the switches 40-2 and 40-3 are open. The frequency regulator 61 comprises a balance-arm and a pair of contact members at each end thereof that are adapted to be engaged selectively, depending upon which way the balance-arm is tilted. Two operating coils are provided which act upon core members secured to the respective extremities of the balance-arm. The circuit of the left-hand operating coil comprises a reactor in series therewith, and the circuit of the right-hand coil comprises a similarly-connected resistor. These two circuits are connected in parallel relation to each other and are energized through conductors 87 and 88 from the secondary winding of a potential transformer 89 (Fig. 1), the primary winding of which is connected across one phase of the circuit of the armature windings 4A of the alternating-current machine 4.

The potential transformer 89 is also connected to the operating coil of an alternating-current voltage regulator 90 (Fig. 1) and to a potential coil of the alternating-current reverse-energy relay 48 (Fig. 1), the current coil of which is energized from one of the current transformers 77. These current transformers also energize current coils in the thermal relay 33, the under-load relay 69, the phase-balance relay 71, and the short-circuit relay 74, as shown. The functions of all of these relays have been described previously.

The frequency regulator 61 is so constructed that, when equal currents traverse its two operating coils, its balance-arm is in a balanced condition, but, when the current traversing the left-hand coil exceeds that traversing the right-hand coil, the balance-arm is tilted to close the right-hand contact members, and vice versa. The reactor and the resistor that are connected in series with the respective coils are so chosen that the impedances of the two coil circuits are equal at the desired frequency of the alternating-current

circuit 1. Therefore, when the machine 4 is generating voltage at the desired frequency, equal currents will traverse the two coils of the frequency regulator 61, since the circuits of these coils are energized in parallel relation to each other from the terminals of the machine 4 through the transformer 89 and the conductors 87 and 88.

If the machine 4 is being driven at too great a speed, the frequency of the voltage generated thereby is also too great, and the frequency regulator 61 must function to reduce the speed of the machine 4. This is accomplished by reason of the fact that the impedance of the circuit of the left-hand coil of the regulator is greater than at normal frequency, since a reactor is connected therein, while the impedance of the circuit of the right-hand coil is substantially unchanged. The right-hand coil is, therefore, more strongly energized than is the left-hand coil and, as a result of this fact, the balance-arm of the regulator is tilted to effect closing of the left-hand contact members. A circuit is thereby completed, extending from the upper terminal of the machine 5, through conductor 51, balance-arm and left-hand contact members of regulator 61, switch 62-1, right-hand field-magnet winding and armature member of motor 60, and conductor 3 to the lower terminal of machine 5.

As previously stated, when the motor 60 is energized in this manner, it operates to decrease the effectiveness of the resistor 63, thereby increasing the excitation of the machine 5. Since the machine 5 is now operating as a direct-current shunt motor, this increase in its excitation causes its speed to decrease, and the frequency of the voltage generated by the machine 4 is correspondingly decreased. In like manner, when the frequency is too low, the energization of the left-hand coil of the regulator 61 is greater than that of the right-hand coil, and the right-hand contact members of this regulator are thereupon closed to effect energization of the motor 60 through its left-hand field-magnet winding. The excitation of the machine 5 is thus decreased and its speed correspondingly increased to effect the proper increase in the frequency of the voltage generated by the machine 4. Thus, it will be seen that, while the machine 5 is operating as a motor to drive the machine 4 as a generator, the regulator 61 controls the speed of the machine 5 through the agency of the motor 60 and the resistor 63 to maintain the frequency of the voltage generated by the machine 4 at the predetermined desired value.

During inverted operation of the machines 4 and 5, it is necessary to maintain the magnitude of the voltage generated by the machine 4 constant at a predetermined value, as well as the frequency of this voltage. This is accomplished by the alternating-current

voltage regulator 90 (Fig. 1), which is similar to the voltage-regulating element 58B of the direct-current voltage regulator 58 (Fig. 2) in every respect except that it is provided with a suitable alternating-current operating coil instead of with a direct-current coil. This operating coil is energized directly from the secondary winding of the transformer 89 (Fig. 1), the primary winding of which is connected to the terminals of the machine 4, as previously set forth. The regulator 90, therefore, operates to close its left-hand contact members when the voltage generated by the machine 4 is below the predetermined desired value, and to close its right-hand contact members when this voltage is above the desired value, in a manner exactly similar to the operation of the voltage-regulating element 58B, previously described in detail.

The left-hand and right-hand contact members of the regulator 90 are connected to the left-hand and right-hand field-magnet windings 91A and 91B of a reversible rheostat-operating motor 91 (Fig. 1) through switches 62—4 and 62—3 (Fig. 1), respectively, of the inversion auxiliary control relay 62 (circuit V—2), which are closed by reason of the energization of this relay during inverted operation of the machines. The balance-arm of the regulator 90 is connected to the upper terminal of the machine 5 through the conductor 51, and the lower terminal of the armature member of the motor 91 is connected to the lower terminal of the machine 5 through the conductor 3, in the same manner that the balance-arm of the voltage-regulating element 58B and the lower terminal of the armature member of the motor 60 are connected.

Thus, in a manner similar to the operation of the element 58B, when the voltage generated by the machine 4 is below the predetermined desired value, the motor 91 is energized through its left-hand field-magnet winding 91A, and this motor thereupon operates to decrease the effectiveness of the resistor 52 which is connected in series with the field-magnet winding 4B of the machine 4. The excitation of the machine 4 and the voltage generated thereby are thereupon correspondingly increased. In like manner, when the voltage of the machine 4 is above the desired value, the motor 91 is energized through its right-hand field-magnet winding 91B to increase the effectiveness of the resistor 52 and thereby to decrease the voltage of the machine 4. Therefore, the voltage regulator 90 is operative during inverted operation of the machines 4 and 5 to maintain the voltage generated by the machine 4 constant at the predetermined desired value.

When the machine 4 is operating as a synchronous motor it is desired that its field-magnet excitation, and hence the effectiveness of the resistor 52, be maintained at a constant predetermined value, corresponding

to the position of the rheostat-operating motor 91 shown in the drawing. This result is accomplished by means of the switches 62—5 and 62—6 of the inversion auxiliary control relay 62 and contact members 92, 93, 94 and 95 that are associated with the motor 91.

The stationary contact member 92 is connected to the conductor 2 of the direct-current circuit through a conductor 96. The contact member 93 is actuated by the motor 91 and always engages the contact member 92. The member 93 also engages either contact member 94 or contact member 95, depending upon whether more or less of the resistor 52 is included in the circuit of the field-magnet winding 4B than is desired when the machine 4 is operating as a motor. When the proper proportion of the resistor 52 is connected in circuit with the winding 4B the contact member 93 is in the position shown in the Fig. 1, in which it does not engage either of the contact members 94 and 95.

When the machine 4 stops operating as a generator the inversion auxiliary control relay 62 is de-energized to permit its switches 62—5 and 62—6 to close. If more than the desired amount of the resistor 52 is then connected in circuit with the winding 4B the contact member 93 will engage contact members 92 and 94 to complete a circuit for energizing the motor 91 through its field-magnet winding 91A. The motor 91 then operates to decrease the effectiveness of the resistor 52.

If not enough of the resistor 52 is connected in the circuit of the winding 4B the contact member 93 will engage contact members 92 and 95 to complete a circuit for energizing the motor 91 through its field-magnet winding 91B. The motor 91 now operates in the reverse direction to increase the effectiveness of the resistor 52. As soon as the contact member 93 reaches the position shown in the drawing the motor 91 is de-energized and operation thereof is stopped. From the above description it will be seen that the effectiveness of the resistor 52 is always automatically adjusted to a predetermined value when inverted operation of the machines stops.

While the direct-current machine 5 is being started as a motor from the direct-current circuit as previously described, the time-delay relay 30 and its clutch coil 30A are energized to effect locking out of the apparatus, in the same manner as described for normal starting, if both machines are not connected to their respective circuits within a predetermined interval of time. The motor coil 30 and the clutch coil 30A of the time-delay relay are then energized through auxiliary switches 18—1 (circuit B—1) and 18—2 (circuit B—2) of the direct-current starting contactor 18 (Fig. 2). If the relay 30 closes its switch 30—3 (circuit C—5) before the alter-

nating-current circuit interrupter 9 is closed, the lock out relay 32 is energized through the switch 30-3 and another auxiliary switch 18-3 (circuit C-51) of the contactor 18 to lock the power apparatus out of service in the same manner as previously described.

If the circuit interrupter 9 is closed within a normal length of time after the contactor 18 is closed, however, the operating coil of the control relay 81 (circuit X) is de-energized because of the opening of the auxiliary switch 9-5 (circuit X) of the interrupter 9. The switch 81-1 (circuit Y) then opens to de-energize the operating coil 18A of the contactor 18, thereby permitting this contactor to open, together with its auxiliary switch 18-1, 18-2, and 18-3. The time-delay relay 30 is then de-energized because of the opening of the switches 18-1 and 18-2, and the switch 30-3 returns to its de-energized position.

In the event that the voltage of the alternating-current circuit 1 fails while the machines 4 and 5 are operating normally, the machines will continue to run, but will immediately invert to supply energy to the alternating-current system. Failure of alternating-current voltage while the machines are operating normally is immediately recognized by the alternating-current reverse-energy relay 48 (Fig. 1) and by the direct-current reverse-current relay 82 (Fig. 2).

The relay 48 opens its switch 48-2 (circuit U) and closes its switch 48-1 (circuit U) thereby de-energizing the relay 49 and causing the switch 49-1 (circuit V) to be closed. The relay 82 opens its switch 82-1 (circuit V) and closes its switch 82-2 (circuit V), thereby effecting energization of the relays 41 (circuit V), 84 (circuit V-1), and 62 (circuit V-2), all in the same manner as previously described. The shunting contactor 85 is closed to shunt the series field-magnet winding 11 of the machine 5 in response to the closing of the switch 84-1 of the relay 84. The operating coil of the normal auxiliary control relay 40 (circuit E) is de-energized by the opening of the switch 41-1 of the inversion master control relay 41 (circuit V), and the switches of the relay 40 are actuated as described before.

The direct-current voltage regulator 58 is now rendered ineffective and the operation of the machines 4 and 5 is controlled by the alternating-current frequency regulator 61 and voltage regulator 90, which have already been described, in full.

Any desired protective devices may be provided to control the inverted operation of the machines 4 and 5, such as an inversion direct-current over-load relay 97 (Fig. 2). The operating coil of the relay 97 is so connected across the shunt 22 (Fig. 2) that its energization is proportional to the value of

current traversing the armature windings of the direct-current machine 5. When this current exceeds a predetermined value the relay 97 closes its switch 97-1 (circuit C) to energize the lock-out relay 32 to preclude further operation of the machines 4 and 5 until the station has been visited by an attendant as previously described.

The alternating-current thermal relay 33 (Fig. 1) is provided with switches 33-3 (circuit V) and 33-4 (circuit V-21) that are adapted to short-circuit the operating coils of the inversion master control relay 41 (circuit V) and the inversion starting control relay 76 (circuit V-21), respectively, when a continued excessive value of current traverses the armature windings of the alternating-current machine 4. Thus if this condition occurs either while the machines are running inverted or while they are starting inverted further operation of the machines will be precluded until the thermal relay 33 returns to its original condition. It is obvious that protective devices could be provided to preclude the operation of the machines, either temporarily or until the station was visited by an attendant, in response to any predetermined conditions occurring while the machines are operating either normally or inverted.

If alternating-current energy becomes available to the circuit, from the normal source while the machines are operating inverted, the machines will immediately revert to normal operation and again become subject to the control apparatus pertaining to normal operation. Such reversion is initiated by the alternating-current reverse-energy relay 48 and the direct-current reverse-current relay 82, which function exactly in the inverse manner to that described for failure of alternating-current voltage while the machines are operating normally. All of the controlling apparatus return to their normal operating conditions and the control of the operation of the machines is transferred from the alternating-current frequency regulator 61 and voltage regulator 90 back to the direct-current voltage regulator 58. This condition of operation has been fully described previously.

From the foregoing description it will be seen that I have provided an automatic station which normally translates energy in one direction between two circuits, but which will translate energy in the reverse direction in response to predetermined conditions. The operation of this station is fully automatic under all conditions and the apparatus therein is fully protected by automatic devices. The system embodying my invention, while fully automatic in its operation, as has been stated, is also readily adaptable to a simple remote controlling and indicating system,

while I also provide. Other novel features of my invention are apparent from the specification and drawings of this application.

I do not wish to be limited to the specific structure and circuit connections of the preferred form of my invention as shown and described herein, as many changes and modifications may be made therein without departing from the spirit and scope of my invention, as set forth in the appended claims.

I claim as my invention:

1. In an electrical system, the combination with two circuits, a rotating translating device, and automatic means for starting and operating the translating device from one of the circuits and for connecting the other circuit to the translating device to receive energy therefrom, of automatic means operative in response to predetermined conditions for starting and operating the translating device from the second-mentioned circuit and for connecting the first-mentioned circuit to the translating device to receive energy therefrom.
2. In an electrical system, the combination with two circuits, a rotating translating device, and automatic means for starting and operating the translating device from one of the circuits and for connecting the other circuit to the translating device to receive energy therefrom under normal conditions, of automatic means operative in response to predetermined abnormal conditions for starting and operating the translating device from the second mentioned circuit and for connecting the first-mentioned circuit to the translating device to receive energy therefrom.
3. In an electrical system, the combination with a direct-current circuit, an alternating-current circuit, and a rotating translating device adapted normally to be started and operated from the alternating-current circuit and to supply energy to direct-current circuit, of automatic means operative in response to predetermined abnormal conditions for causing the translating device to be started and operated from the direct-current circuit, and to supply energy to the alternating-current circuit.
4. In an electrical system, the combination with a direct-current circuit, an alternating-current circuit, and a rotating translating device adapted normally to be started and operated from the alternating-current circuit and to supply energy to the direct-current circuit, of automatic means operative in response to failure of the voltage of the alternating-current circuit for causing the translating device to be started and operated from the direct-current circuit and to supply energy to the alternating-current circuit.
5. In an electrical system, the combination with two circuits and a translating device adapted normally to receive energy from one

of the circuits and to supply energy to the other circuit, of automatic means operative in response to predetermined conditions for causing the translating device to receive energy from the second-mentioned circuit and to supply energy to the first-mentioned circuit, and means for automatically regulating the operation of the translating device in accordance with a characteristic of the circuit that is receiving energy therefrom.

6. In an electrical system, the combination with two circuits and a translating device adapted normally to receive energy from one of the circuits and to supply energy to the other circuit, of means for causing the translating device to receive energy from the second-mentioned circuit and to supply energy to the first-mentioned circuit, and means for automatically regulating the operation of the translating device in accordance with a characteristic of the circuit that is receiving energy therefrom.

7. In an electrical system, the combination with a direct-current circuit, an alternating-current circuit, a translating device, and means for starting and operating the translating device from the alternating-current circuit and for causing the translating device to supply energy to the direct-current circuit, of means automatically responsive to predetermined conditions for causing the translating device to be started from the direct-current circuit, means for regulating the translating device to cause an electrical characteristic thereof to correspond to a characteristic of the alternating-current circuit, and means for connecting the translating device to the alternating-current circuit to supply energy thereto.

8. In an electrical system, the combination with a direct-current circuit, an alternating-current circuit, a translating device, and means for starting and operating the translating device from the alternating-current circuit and for causing the translating device to supply energy to the direct-current circuit, of means automatically responsive to predetermined conditions for causing the translating device to be started from the direct-current circuit, means for regulating the translating device to cause a plurality of electrical characteristics thereof to correspond to the similar characteristics of the alternating-current circuit, and means for connecting the translating device to the alternating-current circuit to supply energy thereto.

9. In an electrical system, the combination with a direct-current circuit, an alternating-current circuit, a translating device, and means for starting and operating the translating device from the alternating-current circuit and for causing the translating device to supply energy to the direct-current

circuit, of means automatically responsive to predetermined conditions for causing the translating device to be started from the direct-current circuit, means for regulating the translating device to cause the voltage thereof to correspond to the voltage of the alternating-current circuit, and means for connecting the translating device to the alternating-current circuit to supply energy thereto.

10. In an electrical system, the combination with a direct-current circuit, an alternating-current circuit, a translating device, and means for starting and operating the translating device from the alternating-current circuit and for causing the translating device to supply energy to the direct-current circuit, of means automatically responsive to predetermined conditions for causing the translating device to be started from the direct-current circuit, means for regulating the translating device to cause the frequency of alternations of the voltage thereof to correspond to the frequency of alternations of the voltage of the alternating-current circuit, and means for connecting the translating device to the alternating-current circuit to supply energy thereto.

11. In an electrical system, the combination with a direct-current circuit, an alternating-current circuit, a direct-current dynamo-electric machine, an alternating-current dynamo-electric machine mechanically connected thereto, a field-magnet winding for the direct-current machine, a resistor in the circuit with said field-magnet winding, and means for controlling the effectiveness of the resistor, of means for causing the alternating-current machine to receive energy from the alternating-current circuit and to drive the direct-current machine to supply energy to the direct-current circuit under predetermined conditions, means for causing the direct-current machine to receive energy from the direct-current circuit and to drive the alternating-current machine to supply energy to the alternating-current circuit under other predetermined conditions, means for controlling the resistor-controlling means to regulate the voltage of the direct-current machine while energy is being supplied to the alternating-current circuit.

12. In an electrical system, the combination with a direct-current circuit, an alternating-current circuit, a direct-current dynamo-electric machine, an alternating-current dynamo-electric machine mechanically connected thereto, a field-magnet winding for the direct-current machine, a resistor in circuit with said field-magnet winding, and means for controlling the effectiveness of the resistor, of means for causing the alternating-current machine to receive energy from the alternating-current circuit and to drive the direct-current machine to supply energy to the direct-current circuit under predetermined conditions, means for causing the di-

for causing the alternating-current machine to receive energy from the alternating-current circuit and to drive the direct-current machine to supply energy to the direct-current circuit under predetermined conditions, 70 means for causing the direct-current machine to receive energy from the direct-current circuit and to drive the alternating-current machine to supply energy to the alternating-current circuit under other predetermined 75 conditions, means for controlling the resistor-controlling means to regulate the voltage of the direct-current machine to correspond to the voltage of the direct-current circuit prior to the effecting of connection therebetween, 80 and means for controlling the resistor-controlling means to regulate the speed of the dynamo-electric machines while energy is being supplied to the alternating-current circuit.

13. In an electrical system, the combination with a direct-current circuit, an alternating-current circuit, a direct-current dynamo-electric machine, an alternating-current dynamo-electric machine mechanically connected 90 thereto, a field-magnet winding for the direct-current machine, a resistor in circuit with said field-magnet winding, and means for controlling the effectiveness of the resistor, 95 of means for causing the alternating-current machine to receive energy from the alternating-current circuit and to drive the direct-current machine to supply energy to the direct-current circuit under predetermined conditions, means for causing the direct-current 100 machine to receive energy from the direct-current circuit and to drive the alternating-current machine to supply energy to the alternating-current circuit under other predetermined 105 conditions, means for controlling the resistor-controlling means to regulate the voltage of the direct-current machine while energy is being supplied to the direct-current circuit, and means for controlling the resistor-controlling means to regulate the frequency 110 of alternations of the voltage of the alternating-current machine to correspond to the frequency of alternations of the voltage of the alternating-current circuit prior to the effecting of connection therebetween.

14. In an electrical circuit, the combination with a direct-current circuit, an alternating-current circuit, a direct-current dynamo-electric machine, an alternating-current dynamo-electric machine mechanically connected 120 thereto, a field-magnet winding for the direct-current machine, a resistor in circuit with said field-magnet winding, and means for controlling the effectiveness of the resistor, of means for causing the alternating-current machine to receive energy from the alternating-current circuit and to drive the direct-current machine to supply energy to the direct-current circuit under predetermined 125 conditions, means for causing the di-

rect-current machine to receive energy from the direct-current circuit and to drive the alternating current machine to supply energy to the alternating-current circuit under other predetermined conditions, means for controlling the resistor-controlling means to regulate the voltage of the direct-current machine to correspond to the voltage of the direct-current circuit prior to the effecting of connection therebetween, and means for controlling the resistor-controlling means to regulate the frequency of alternations of the voltage of the alternating-current machine to correspond to the frequency of alternations of the voltage of the alternating-current circuit prior to the effecting of connections therebetween.

15. In an electrical system, the combination with a direct-current circuit, an alternating-current circuit, a direct-current dynamo-electric machine, an alternating-current dynamo-electric machine mechanically connected thereto, a field-magnet winding for the alternating-current machine, a resistor in circuit with said field-magnet winding, and means for controlling the effectiveness of the resistor, of means for causing the alternating-current machine to receive energy from the alternating-current circuit and to drive the direct-current machine to supply energy to the direct-current circuit under predetermined conditions, means for causing the direct-current machine to receive energy from the direct-current circuit and to drive the alternating-current machine to supply energy to the alternating-current circuit under other predetermined conditions, means for controlling the resistor-controlling means to regulate the voltage of the alternating-current machine while energy is being supplied to the alternating-current circuit, and means for controlling the resistor-controlling means to cause the resistor to have a predetermined definite effectiveness while energy is being supplied to the direct-current circuit.

40 16. In an electrical system, the combination with a circuit and a dynamo-electric machine, means for causing the circuit to supply energy to the dynamo-electric machine under predetermined conditions and means for causing the dynamo-electric machine to supply energy to the circuit under other predetermined conditions, of means for varying the field-magnet excitation of the dynamo-electric machine to regulate the voltage thereof while the machine is supplying energy to the circuit, and means for automatically adjusting said field-magnet excitation to a predetermined definite value before the circuit begins to supply energy to the machine.

45 17. In an electrical system, the combination with a circuit, a dynamo-electric machine, a field-magnet winding therefor, a resistor in circuit with the field-magnet winding, and means for controlling the effectiveness of the

resistor, of means for causing the circuit to supply energy to the dynamo-electric machine under predetermined conditions and means for causing the dynamo-electric machine to supply energy to the circuit under other predetermined conditions, means for controlling the resistor-controlling means to regulate the voltage of the dynamo-electric machine while the machine is supplying energy to the circuit, and means for automatically controlling the resistor-controlling means to adjust the effectiveness of the resistor to a predetermined definite value before the circuit begins to supply energy to the machine and for maintaining such effectiveness of the resistor while the circuit is supplying energy to the machine.

50 18. In an electrical system, the combination with a direct-current circuit, an alternating-current circuit, a direct-current dynamo-electric machine, an alternating-current dynamo-electric machine mechanically connected thereto, a field-magnet winding for the alternating-current machine, a resistor in circuit with said field-magnet winding, and means for controlling the effectiveness of the resistor, of means for causing the alternating-current machine to receive energy from the alternating-current circuit and to drive the direct-current machine to supply energy to the direct-current circuit under predetermined conditions, means for causing the direct-current machine to receive energy from the direct-current circuit and to drive the alternating-current machine to supply energy to the alternating-current circuit under other predetermined conditions, a voltage regulator associated with the alternating-current circuit for controlling the resistor-controlling means to maintain the voltage of the alternating-current circuit substantially constant at a predetermined value while energy is being supplied thereto by the alternating-current machine, and means comprising a positioning switch associated with the resistor-controlling means for causing said resistor-controlling means to adjust the effectiveness of the resistor to a predetermined value when the alternating-current machine begins to receive energy from the alternating-current circuit.

55 19. In an electrical system, in combination, two circuits, two mechanically connected dynamo-electric machines respectively connected to the circuits, means for causing either machine to operate as a motor and the other as a generator, means for varying the excitation of one of the machines while it is operating as a generator in accordance with the voltage of the circuit to which said machine is connected, and means for adjusting the excitation of said machine to a predetermined value when said machine is to operate as a motor.

60 20. In an electrical system, in combination, two circuits, two mechanically connected dynamo-electric machines respectively con-

- 5 nected to the circuits, means for causing either machine to operate as a motor and the other as a generator, a series field-magnet winding for one of the machines and means operative in response to a condition indicating that said machine is operating as a motor for rendering said series field-magnet winding ineffective.

10 21. In an electrical system, in combination, an alternating-current circuit, a direct-current circuit, an alternating-current dynamo-electric machine, a direct-current dynamo-electric machine, said dynamo-electric machines being mechanically connected, means for causing either of said machines to receive energy from the corresponding circuit to operate as a motor and to drive the other of said machines as a generator to supply energy to the other circuit, a series field-magnet winding for the direct-current dynamo-electric machine, and means responsive to a condition indicating that the direct-current dynamo-electric machine is operating as a motor for rendering said series field-magnet winding ineffective.

15 22. In an electrical system, in combination, an alternating-current circuit, a direct-current circuit, an alternating-current dynamo-electric machine, a direct-current dynamo-electric machine, said dynamo-electric machines being mechanically connected, means for causing either of said machines to receive energy from the corresponding circuit to operate as a motor and to drive the other of said machines as a generator to supply energy to the other circuit, a series field-magnet winding for the direct-current dynamo-electric machine, and means responsive to the direction of energy traversal of one of the circuits for short-circuiting said series field-magnet winding when the direct-current dynamo-electric machine is operating as a motor.

20 23. In an electrical system, in combination, an alternating-current circuit, a direct-current circuit, an alternating-current dynamo-electric machine, a direct-current dynamo-electric machine, said dynamo-electric machines being mechanically connected, means for causing either of said machines to receive energy from the corresponding circuit to operate as a motor and to drive the other of said machines as a generator to supply energy to the other circuit, a series field-magnet winding for the direct-current dynamo-electric machine, and means responsive to the direction of energy traversal of the direct-current circuit for short-circuiting said series field-magnet winding when the direct-current dynamo-electric machine is operating as a motor.

25 24. In an electrical system, in combination, an alternating-current circuit, a direct-current circuit, an alternating-current dynamo-electric machine, a direct-current dynamo-electric machine, said dynamo-electric machines being mechanically connected, means for causing either of said machines to receive energy from the corresponding circuit to operate as a motor and to drive the other of said machines as a generator to supply energy to the other circuit, a series field-magnet winding for the direct-current dynamo-electric machine, and means responsive to the direction of energy traversal of the direct-current circuit for short-circuiting said series field-magnet winding when the direct-current dynamo-electric machine is operating as a motor.

30 25. In an electrical system, in combination, a dynamo-electric machine, a source of energy, means for reducing the electro-motive force of the source of energy, a starting circuit interrupter connected between the reduced electro-motive force means and the dynamo-electric machine, a running circuit interrupter connected between the source of energy and the dynamo-electric machine, a closing coil for each of said circuit interrupters, means for maintaining each of said circuit interrupters closed after its closing coil has been energized for a relatively short interval of time, means for selectively energizing said closing coils to effect connection between the reduced electromotive force means and the dynamo-electric machine to start said machine from rest and to bring it up to substantially its normal operating speed and then to effect connection between the source of energy and the dynamo-electric machine to cause said machine to operate normally, and a single time-delay cut-off means for effecting deenergization of each of said closing coils after it has been energized for a predetermined interval of time.

35 26. In an electrical system, in combination, a dynamo-electric machine, a source of energy, means for reducing the electro-motive force of the source of energy, a starting circuit interrupter connected between the reduced electro-motive force means and the dynamo-electric machine, a running circuit interrupter connected between the source of energy and the dynamo-electric machine, a closing coil for each of said circuit interrupters, means for maintaining each of said circuit interrupters closed after its closing coil has been energized for a relatively short interval of time, means for energizing the closing coil of the starting circuit interrupter, a transfer relay, means for energizing the transfer relay after the starting circuit interrupter has been closed, a tripping coil for the starting circuit interrupter, a switch closed by the transfer relay when said relay is energized for effecting energization of said tripping coil, a control relay for effecting energization of the closing coil of the running circuit interrupter when said control relay is energized, means responsive to the energization of the transfer relay and the tripping of the starting circuit interrupter

for effecting energization of said control relay, a time-delay cut-off relay adapted to effect opening of the circuit of the closing coil of each of the circuit interrupters when said 5 cut-off relay has been energized for a predetermined interval of time, a switch actuatable by the control relay for the closing coil of the running circuit interrupter to connect the cut-off relay in parallel relation to the 10 closing coil of the starting circuit interrupter when said control relay is de-energized, and a switch actuatable by the transfer relay for connecting the cut-off relay in parallel relation to the closing coil of the running circuit 15 interrupter when said transfer relay is energized.

27. In an electrical system, in combination, a power circuit, a dynamo-electric machine, automatic means for starting the dynamo- 20 electric machine from rest and connecting it to the power circuit to supply energy thereto, a relay for initiating operation of the

automatic means, a relay for stopping operation of the dynamo-electric machine and disconnecting it from the power circuit, an 25 auxiliary control conductor, means controlled by the connection of the dynamo-electric machine to the power circuit for varying the electrical resistance between one conductor of the power circuit and the auxiliary control conductor, and a control station connected only to the power circuit and the auxiliary control conductor and comprising a starting switch for effecting energization of the initiating relay, a stopping switch for effecting energization of the stopping relay and an indicating device connected between the auxiliary control conductor and another conductor of the power circuit.

In testimony whereof, I have hereunto subscribed my name this 22nd day of September, 1924.

ROY J. WENSLEY.
